Primary Examiner—Robert M. Spear*Assistant Examiner*—Susan Bennett Hattan(74) *Attorney, Agent, or Firm*—Gifford, Krass, Groh, Sprinkle, Anderson & Citkowski, P.C.(57) **CLAIM**

The ornamental design for a dual opening round container lid, as shown and described.

DESCRIPTION

FIG. 1 is a perspective view of the dual opening round container lid with a large flap in an open position;

FIG. 2 is another perspective view of the inventive lid of FIG. 1 with a small flap in an open position;

FIG. 3 is a top view of the inventive lid depicted in FIG. 1 with both flaps in a closed position;

FIG. 4 is a front view of the inventive lid depicted in FIG. 3;

FIG. 5 is a right side view of the inventive lid depicted in FIG. 3; and,

FIG. 6 is a right side view of the inventive lid in FIG. 2 with both flaps in an open position.
